COVER FOR ANCHOR NUTS ON THE BASE OF AN OUTDOOR STANDARD

Gordon E. Daniels, Bear Road, Nashville, Tenn.

Filed June 15, 1961, Ser. No. 65,599

Term of patent 7 years

(Cl. D48—4)

FIG. 1 is a front elevational view of a cover for anchor nuts on the base of an outdoor standard, embodying my new design;

FIG. 2 is a section taken along the line 2—2 of FIG. 1; and

FIG. 3 is a perspective view thereof.

I claim:

The ornamental design for a cover for anchor nuts on the base of an outdoor standard.
